Freeman Halbrook.

UNITED STATES PATENT OFFICE.

FREEMAN HALBROOK, OF MAYFIELD, KENTUCKY.

CAR-COUPING.

SPECIFICATION forming part of Letters Patent No. 387,352, dated August 7, 1888.

Application filed September 22, 1887. Serial No. 250,441. (No model.)

To all whom it may concern:

Be it known that I, FREEMAN HALBROOK, a citizen of the United States, residing at Mayfield, in the county of Graves, in the State of Kentucky, have invented an Improved Plan for Coupling Railroad-Cars, of which the following is a specification.

My invention relates to an improvement in car-couplings; and it consists in the combination of the two coupling-heads and the coupling pins and links with two projections each one of which extends in advance of its coupling-head, the supporting-plates, which are pivoted at one end and extend through horizontal slots made through the coupling-heads, and the operating-levers connected to these supporting-plates and by which the plates are moved into any desired position, as will be more fully described hereinafter.

The object of my invention is to provide a car-coupling which is automatic in its operation and in which the pin is supported in a raised position until the cars run together, when the support is forced from under the pin and it drops through the link and couples the cars together.

Figure 1 is a side elevation of a car-coupling which embodies my invention, one of the couplings having a portion of the timbers broken away, so as to show its parts in one position in solid lines and another position in dotted lines. Fig. 2 is a plan view of the same.

A represents the timbers of the cars, and 1 2 the draw-heads, which are secured therein in any suitable manner. The opening in each draw-head for the reception of the end of the link is made largest at its outer end and tapers backward, as shown in dotted lines, toward 40 the rear end, where the opening is just large enough to freely admit the end of the link.

The coupling-pins P are of the ordinary construction, and couple with the link in the usual manner.

Secured to the timbers A of each car is a projection, D, which extends a suitable distance in advance of its coupling-head, and which projection has its front end reduced in width, so as to freely enter the space between

the outer timbers of the opposite car and the draw-head which is secured therein, as shown in Fig. 2. Pivoted in each one of these projections D and extending horizontally through a suitable slot or opening which is made through the draw-head is a supporting-plate, 55 E, which has an opening made through its outer end, where it projects beyond the side of the coupling, and in which opening the lower end of the lever L, pivoted upon the side of the draw-head, catches. By means of this 60 lever L the supporting-plate E can be moved back and forth so as to catch under the raised pin and support it in an elevated position, as shown in dotted lines in Fig. 1, or it can be moved backward, so as not to interfere with 65 the pin in any respect. When the pin P is raised upward and the upper end of the lever L is forced backward, the free end of the plate 70 E is moved forward and its central portion catches under the lower part of the pin and supports the pin in a raised position ready for coupling.

When the cars run back, the projection D upon the opposite car strikes against the free end of the supporting-plate E and forces it 75 backward, so that the plate E is moved from under the pin and the pin drops through the link F, as shown.

By this construction the draw-heads can be set so as to automatically couple when they 80 run together, or the pins can be left so as not to couple, as may be desired.

Having thus described my invention, I claim—

The combination of the draw-heads having 85 horizontal slots made through them, the extensions D, having their front ends projecting beyond the draw-heads, the pivoted supports extending through the slots in the draw-heads, the operating-levers pivoted on the draw-heads, the pins, and the link, substantially as 90 shown and described.

March 1, 1887.

FREEMAN HALBROOK.
